Attorney.

UNITED STATES PATENT OFFICE.

CARL SCHANTZ, OF FREIBURG, GERMANY.

METHOD OF PRESERVING WOOD AND THE LIKE.

Application filed January 25, 1927, Serial No. 163,517, and in Germany January 16, 1926.

The invention relates to a method of and an implement for preserving wood and the like.

It is known to preserve wood and the like by incorporating the preserving agent with the wood through radial or axial holes, which are produced by piercing, drilling or in any other suitable manner.

There is also known a method for preserving wood in which a piercing implement in the form of a hollow pin is employed through the bore of which the preserving agent penetrates into the wood when the pin is forced into the wood or withdrawn from it.

In all these methods of impregnating wood it is only possible to charge the preserving agent into the cavities produced by the implements or tools in the wood after the 20 piercing tools have been withdrawn from the wood. The period between the moment when the tools leave the cavities produced by them and the time at which the preserving substance penetrates into the cavities in 25 the wood, is a matter of indifference for the preserving action.

For this reason all the methods employed heretofore labor under the drawback that the preserving agents cannot be forced 30 under pressure into the wood or that large boilers are necessary in which the wood must be preserved in its entire length.

The present invention eliminates these drawbacks by spreading the wood in its 35 longitudinal direction for a few centimetres slightly apart or splitting it by means of a suitable designed piercing tool, so that the preserving agent may be forced under pressure into the split wood while the piercing 40 pin is still located in the wood. The piercing pin is a solid, preferably wedge-shaped pin. This solid pin is in any suitable manner combined with a charging device which surrounds the said pin at its upper end. 45 The lower end of the charging device surrounds the upper portion of the solid pin in such a manner that a small annular or otherwise shaped space is left between the solid pin and the charging device through 50 which the preserving agent is able to penetrate into the wood. At the charging device is provided a non-return valve which permits the preserving agent introduced into the wood to be left within the wood under a 55 pressure of any desired height. On account of the possibility of forcing the preserving

agent into the wood under pressure, the preserving agent distributes itself widely into the wood already during the forcing process, so that the pierced openings may be provided at comparatively long distances apart. 60

The drawing affixed hereto shows an embodiment of the invention by way of example. In it is:

Fig. 1, a longitudinal section through the 65 broad side of the piercing tool,

Fig. 2, a longitudinal section through the narrow side of the piercing tool,

Fig. 3, a cross-section along line 1—1 of Fig. 1, and

Fig. 4, a cross-section along line 2—2 of Fig. 2.

Like parts are indicated by like reference letters in all the figures of the drawing.

Referring to the drawing, A is the solid 75 pin which is driven into the wood or other material to be preserved until the charging device B provided with means C for forming a seal against the wood firmly rests upon the surface of the wood. The charging device is equipped with a non-return valve D, upon which is placed a force pump of any desired kind. The preserving agent is forced by this pump through the non-return valve D into the charging device B and flows 80 through the annular space E between the solid pin A and the charging device B along the pin into the wood slightly spread apart by the pin where it distributes itself due to the pressure of the pump. 90

Various modifications and changes may be made without departing from the spirit and the scope of the invention, and I desire, therefore, that only such limitations shall be placed thereon as are imposed by the prior 95 art.

I claim as my invention:

1. Method of preserving wood and the like, which consists in forcing the preserving agent under pressure along a piercing device into the wood, said piercing device remaining in the wood during the forcing in of the preserving agent. 100

2. In a device for preserving wood, in combination, a solid pointed pin adapted to be forced into the wood and a charging device around the upper portion of said pin through which the preserving agent is adapted to be forced along said pin into the spread apart wood. 105

3. In a device for preserving wood, in combination, a solid pointed pin adapted to 110

be forced into the wood, and a charging device surrounding the upper projecting portion of said pin and leaving an annular space between itself and said pin through which the preserving agent is adapted to be forced along said pin into the spread apart wood.

4. In a device for preserving wood, in combination, a solid pointed pin adapted to be forced into the wood, a charging device surrounding the upper projecting portion of

said pin and leaving an annular space between itself and said pin through which the preserving agent is adapted to be forced along said pin into the spread apart wood, a non-return valve upon said charging device, and a force pump connected with said valve.

In testimony whereof I have affixed my signature.

CARL SCHANTZ.
